UNITED STATES PATENT OFFICE

EDWARD H. POLK, OF SACRAMENTO, CALIFORNIA

SKID AND LIFT TRUCK MEANS FOR HANDLING MATERIALS

Application filed October 24, 1930. Serial No. 490,913.

My invention relates to the art of handling materials by skid and lift-truck means; an art which in practice has been extensively applied in connection with the storing, shipping, and other disposal and convenient use of a variety of manufactured supplies especially in and about railroad shops.

In this art the essential factors involve the initial placing of the articles upon a raised platform, commonly known as a skid, and then introducing under the loaded skid a truck adapted to lift it from its position of rest and transport it to and leave it at its destination.

It is evident that in order to carry out such practice one feature must be present under all conditions and circumstances, namely, that the skid must, in its position of rest while being loaded, be raised to a sufficient height to enable the lift-truck jack-extension to be run in under it. As far as I am aware this necessity has hitherto been met by providing the skid with legs or bottom projections of some kind which are a permanent part of the skid. Whatever form these leg supports may assume they detract from the space in which the skids may be packed in storing or shipping and are thus not economical.

Furthermore, such skids are commonly used for the temporary storage of materials, and also for the transportation thereof in railway cars or other vehicles, the object being to reduce storage and transportation costs by minimizing handling. Such uses, however, require great numbers of skids, with consequently large capital investment, the number required depending not only upon the amount of material, but also upon the length of time it remains in storage or transit. Moreover, when the skids are empty, and especially when being returned empty in cars or vehicles, they occupy considerable space, on account of their legs.

It is the object of my invention to effect greater economy by reducing the capital investment required for a given number of skids, and by conserving the packing, storing and shipping space; and to this end my invention comprises a legless skid in associa-

tion with spaced supporting members or rails, either fixed or movable, but independent of the skid, and of dimensions adapted to raise it sufficiently for the introduction beneath it of the lift-truck extension. Capital investment is reduced because my flat skids and their independent supporting rails can be built at much less cost than those having permanent legs, and further because it is unnecessary to supply supports for all skids, a certain proportion thereof being always in transit. Space is saved because the flat skids, whether loaded or empty, can be placed directly upon the floor of a car or other vehicle, or, when empty, can be stacked on edge in otherwise unused spaces.

When the storage of material is in permanent locations, the supporting rails can be fixed to the ground or floor, and can be cheaply constructed, preferably of timber. However, said rails can be movable, if desired, thus providing flexibility practically equal to that of the commonly used leg skids. Both these developments of the invention are illustrated and described herein in their preferred forms, though it must be understood that changes may be made without departing from the spirit of the invention as defined by the claim hereunto appended.

In the drawings—
Fig. 1 is a perspective view showing two of my skids resting upon fixed rails.

Fig. 2 is an end view of the skid.

Fig. 3 is a front elevation showing the skids resting upon movable supporting rails.

Fig. 4 is a side elevation of the form of movable support shown at the left of Fig. 3, adapted to hold a single rail.

Fig. 5 is a side elevation of the form of movable support shown at the right of Fig. 3, adapted to hold two parallel rails.

The reference numeral 1 designates my skid, which comprises a substantially flat platform or body portion, upon which the material to be stored or transported may be piled. The skid is preferably, though not necessarily, made of mortised wooden strips 2, Figs. 1 and 2, whose ends are confined between reinforcing strips 3 and 4 held together by bolts 5. The strips 3 on the top of the

skid serve as retaining flanges to prevent the piled material (not shown) from sliding off, and the strips 4 on the bottom serve as bearing flanges on which the skid rests. The 5 skid is reversible, either side being the top.

6 in Fig. 1 are rails spaced apart a distance substantially equal to the spanning capacity of the skid which rests upon them. These rails, which are preferably formed of wooden 10 timbers, with separate wearing faces 7, are fixed in place, as for example by angle brackets 8, and have a height adapted to raise the skid sufficiently to permit the lift extension of the usual transporting truck, 15 unnecessary herein to show, to pass in under the loaded skid; and upon operating its elevating jacks, to lift the skid from the rails and carry it off to a destination, which may be another group of rails upon which it is 20 deposited, for temporary convenience or storing purposes; or the skid may be directly lifted from the truck and deposited in cars for shipping. In practice the supporting rails 6 may be a group more or less extensive 25 adapted for a number of skids, as is indicated in Fig. 1.

Fig. 3 illustrates a type of supporting rail structure having the same function as that of Fig. 1, but adapted to be moved from place to 30 place as circumstances of loading or storing may demand. 9 and 9' are supporting stands having feet 10 and 10' suitably spread to insure stability, and brackets 11 and 11' adapted to hold either one or two rails 12 respectively. 35 The rails 12 may be of any suitable nature, such as scrap railway rails, as shown. The stands 9 and 9' are placed upon the ground or floor in the proper relative positions, and the rails 12 laid in the brackets 11 and 11', 40 the whole forming a pair or group of parallel supports upon which the skids 1 may be placed, in the same manner as upon the fixed rails 6 of Fig. 1.

Where but one line of skids, i. e. two rails, 45 is required, the stands may be of the form shown at 9 in Figs. 3 and 4, in which a single piece of flat iron is bent at its upper end to form the U-shaped bracket 11, and at its lower end to form one of the feet 10, the other 50 feet being formed by a second piece 13 welded or otherwise secured at 14 to the upright portion of the first piece. If a plurality of pairs of rails are required, the single stands 9 may be used for the outside rails, but the inner 55 rails, arranged in pairs as shown at the right in Fig. 3, are preferably supported upon stands of the form shown at 9' in Figs. 3 and 4, in which a double U-shaped bracket 11' is welded or otherwise secured as at 15, to the 60 apex of an inverted V-shaped standard of flat iron whose lower ends are bent horizontally in opposite directions to form the feet 10'.

Whether the supporting rails are per- 65 manently fixed in position, as in Fig. 1, or

are portable, as in Fig. 3, the essential principle of the invention is the same, viz:—that the skids are legless platforms, that is to say their under surfaces are substantially flat, and the supporting members by which they are raised in rest position are independent of them; wherefore they can be manufactured at minimum cost and stored or shipped with maximum space economy, which are the ends sought. 70

I claim:—

Apparatus for handling materials by lift-trucks, in the described art, comprising a plurality of independent legless skids contiguously freely assembled in an elevated horizontal plane; a plurality of rails upon which the assembled skids freely rest; a plurality of stands for supporting said rails in elevated position; single brackets on the stands carrying the rails which support the skid assemblage along its outer sides; and double brackets on the stands carrying the rails which support the skid assemblage intervening its outer sides. 80

In testimony whereof I have signed my 90 name to this specification.

EDWARD H. POLK.
